[57] **CLAIM**

The ornamental design for a wall mounted garage door control, as shown and described.

DESCRIPTION

FIG. 1 is a front elevational view of a wall mounted garage door control showing a first embodiment;

FIG. 2 is a right-hand side elevational view thereof;

FIG. 3 is a bottom plan view thereof;

FIG. 4 is a top plan view thereof;

FIG. 5 is a rear elevational view thereof, with the broken line showing for illustrative purposes only and forming no part of the claimed design;

FIG. 6 is a left-hand side elevational view thereof;

FIG. 7 is a top plan view of a wall mounted garage door control showing a second embodiment of our new design;

FIG. 8 is a left-hand side elevational view thereof;

FIG. 9 is a right-hand side elevational view thereof;

FIG. 10 is a front elevational view thereof, with the rear being the same as FIG. 5; and,

FIG. 11 is a bottom plan view thereof.
